RIBBON MECHANISM

Paul J. Schlessiger and Lee Smith, Endicott, N. Y., assignors to International Business Machines Corporation, New York, N. Y., a corporation of New York

Application December 24, 1952, Serial No. 327,897

3 Claims. (Cl. 101—336)

This invention relates to means under the control of an inking ribbon for automatically and concurrently reversing the movement of ribbon feed in a longitudinal direction, shifting the ribbon in a transverse direction, and changing the point of ribbon reinking. 15

The advent of relatively high speed printing machines, particularly those of the line-by-line type, has made it necessary to find ways and means to make inking ribbons last a reasonable length of time, and at the same time to produce good, legible, printed records from those ribbons. This problem is of particular importance when considered from the standpoint of maintenance; i. e., making it unnecessary to replace the ribbons very frequently while the machines are in use. 20

Accordingly, an object of this invention is to provide improved means for extending the useable life of an inking ribbon.

For illustrative purposes, the instant invention is shown applied to a line-by-line printer of the general type shown and described in U. S. Patent No. 2,438,071, issued March 16, 1948, to R. E. Page et al. However, it is not intended to limit the use of this invention to this particular type of printing machine as the invention lends itself for use with many other types of printers.

In order to be able to produce properly inked printed records from printing machines of the aforementioned type, the condition of the inking ribbon must be controlled so that the desired wetness of the ribbon can be maintained for the life of the ribbon. In other words, the ribbon must not be permitted to become too dry nor too wet.

It is known that the drier the ribbon, the more subject it is to wear from impact with the printing type members. A properly inked ribbon will stand up longer than a dry ribbon, and consequently the user of a machine having a properly inked ribbon thereon saves both time and money.

It is also known that the wetter the ribbon, the more likely it is for the excess ink to run between the various printing type members, and cause the same to stick and to eventually misprint. In addition thereto, an excessively wet ribbon causes smearable printing to render poor printed records.

Generally, inking ribbons used in machines of the aforementioned kind, are of the type adapted to be wound on alternately drivable spools. This fact is taken advantage of in the present method of reinking the ribbon in that ink is applied to the ribbon just prior to winding the same on a spool and during the feeding movement thereof only. This method of reinking permits a more even distribution of the ink applied to the ribbon throughout the entire ribbon, and allows for the proper wetness of the ribbon so that it is never over-inked.

Most inking ribbons adapted to be wound on alternately drivable spools are wide enough to afford two longitudinal printing areas to the printing type members of a machine. Thus, the useable life of a ribbon may be lengthened appreciably by utilizing the two said printing

2

areas. This is accomplished in the present method by shifting the ribbon in a transverse direction when reversing the direction of feed of the ribbon so as to alternate between the two longitudinal ribbon areas.

Accordingly, another object of this invention is the provision of means under the control of an inking ribbon to automatically and concurrently reverse the movement of ribbon feed in a longitudinal direction, shift the ribbon in a transverse direction, and change the point of ribbon reinking so that the ribbon is reinked just prior to being wound on a winding spool. 10

In line with the foregoing, a more specific object of this invention resides in the provision of means under the control of a continuously moving inking ribbon for automatically and concurrently reversing the movement of ribbon feed in a longitudinal direction, shifting the ribbon in a transverse direction, and changing the point of ribbon reinking so that the ribbon is reinked just prior to being wound on a winding spool, when a ribbon winding spool becomes empty. 20

A still more specific object of this invention is to provide means for continuously reinking an inking ribbon moving alternately in forward and reverse directions just prior to winding the inking ribbon on to a winding spool.

Other objects of the invention will be pointed out in the following description and claims and illustrated in the accompanying drawings, which disclose, by way of example, the principle of the invention and the best mode, which has been contemplated, of applying that principle. 25

In the drawings:

Fig. 1 is a plan view of the ribbon feeding and reinking mechanism on a printing machine.

Fig. 2 is a front elevation of the left hand section of the mechanism taken along line 2—2 of Fig. 1.

Fig. 3 is an electrical diagram showing circuits relating to the ribbon feeding and reinking.

Fig. 4 is a sectional view taken along the line 4—4 of Fig. 2.

Fig. 5 is a somewhat diagrammatic view of the reinking apparatus of the left hand section of the ribbon feeding and reinking mechanism.

Fig. 6 is a sectional view taken along the line 6—6 of Fig. 2.

General operation

Referring to Fig. 1, the inking ribbon 10 is caused to move continuously past the printing wheels 11 by the alternately driven winding spools 12 and 13. The said spools advance the ribbon first in one direction, e. g., from left to right, and then advance the ribbon in the reverse direction when a winding spool is empty. The change in direction of the feed of the ribbon occurs each time a winding spool becomes empty.

As is shown in Fig. 1, the ribbon 10 is threaded between the winding spools 12 and 13 through the following path: starting at the left winding spool 12, the ribbon passes between the left switch actuating arm 14 and the ribbon guide plate 15; around the ribbon roller guide 16, the left reinker roller 17, and the ribbon roller guide 18; between the printing wheels 11 and the platen 19; around the ribbon roller guide 20, the right reinker roller 21, and the ribbon roller guide 22; between the right switch actuating arm 23 and ribbon guide plate 24; and onto the right winding spool 13.

When a winding spool, for example spool 12, is nearly empty, an eyelet 30 which is fastened to the left end portion of the inking ribbon engages the left switch actuating arm finger 31 in order to move the said arm in a counterclockwise direction as ribbon 10 advances from spool 12 to spool 13. This causes a lateral extension 32 of arm 14, shown more clearly in Fig. 2, to strike a left switch operating arm 33 so as to operate a switch 34. As

to be explained more fully in the circuit description, operation of the said switch causes the following actions to take place concurrently: (a) the engagement of the left winding spool clutch in order to drive spool 12 in a clockwise direction, and the disengagement of the right winding spool clutch so as to render spool 13 free-moving; 5 (b) the counterclockwise movement of reinker roller engaging arm 78 (Fig. 1) in order to cause contact between reinker roller 17 and a left reinker wick 35 (see also Fig. 5); and the counterclockwise movement of reinker roller engaging arm 29 in order to separate the reinker roller 21 and right reinker wick 36; (c) and a downward transverse movement of the ribbon in order to present the upper longitudinal ribbon printing area to the printing 10 wheels 11.

Throughout this entire description, reference will be made to the upper and lower longitudinal ribbon printing areas. With reference to Fig. 5, the longitudinal area ribbon 10 above the ribbon center line 37 will be termed the upper printing area, and the longitudinal area of ribbon 10 below center line 37 will be termed the lower printing area.

As mentioned hereinbefore, for illustrative purposes the instant invention is shown applied to a line-by-line printer of the general type shown and described in U. S. Patent No. 2,438,071, issued March 16, 1948, to R. E. Page et al. The said printer is fully described in the said patent and in order to avoid undue prolixity, will be described only briefly herein.

With reference to Fig. 1 each printing wheel 11 is 30 carried by an arm 25 loosely pivoted upon a rod 26. During print time, arm 25 is rocked about the rod 26 against the action of a return spring 28 so that the printing wheel 11 associated therewith is moved toward the platen 19 to strike the same squarely and firmly to cause a legible impression.

Ribbon feeding and reinking mechanism

In view of the fact that the left hand and right hand ribbon feeding and reinking mechanisms 40 and 41, respectively, are similar, only the left hand mechanism 40 will be described herein in order to avoid prolixity.

Referring to Fig. 2, main drive shaft 42, driven continuously by a motor 43 (Fig. 3), causes a left winding spool drive shaft 44 and a right winding spool drive shaft (not shown) to revolve continuously. The left drive shaft 44 has attached thereto a bevel gear 45 for driving a right winding spool intermediate shaft 46 which, in turn, has attached thereto at its right end, a bevel gear (not shown) similar to gear 47 for driving the right winding spool shaft.

The left shaft 44 has a clutch gear drive plate 48 fixedly attached to its upper end; the said plate having three drive studs 49 (Fig. 6) projecting therefrom and normal thereto. A winding spool clutch gear 50 is arranged on plate 48 so that openings 55 in the said gear are aligned with the drive studs 49. Gear 50 is held in position on the said plate by a spider spring 56 which, in turn, is held in position by a spring retainer 57.

The left winding spool driven shaft 58 (Fig. 2) has a winding spool gear 59 and a drive bushing 60 fixed thereto. A driving pin 61 projects from both ends of the bushing. One end of pin 61 extends within an opening in the under side of winding spool 12 while the other end extends through a spring 65 and within a brake disc 62. Winding spool 12 is held in place on bushing 60 by a knurled nut 66 which is threaded onto driven shaft 58. Thus, when the drive bushing 60 is caused to revolve, the winding spool 12 and the brake disc 62 are caused to revolve therewith by the connecting action of pin 61.

Brake disc 62 is lined with a brake material 63 which is in contact with the upper surface of the ribbon mechanism support plate 64. A spider spring 65 positioned between bushing 60 and disc 62 affords a suitable pressure between the brake material 63 and the support plate 64.

The braking action resulting therefrom is highly desirable in order to avoid undue strain on inking ribbon 10 during ribbon reversals. When a ribbon reversal occurs, the rotation of the winding spools is rapidly reversed; i. e., to be more accurate, the spools decelerate to a momentary stop, and then accelerate to full speed in the other direction. If there were no braking action to decelerate the ribbon, during ribbon reversal time the winding spools would be snapped from one direction to the other. This would create an undue strain on the ribbon.

As is shown in Fig. 6, a clutch engaging cam arm 70 is connected to core 71 of the left reinker and reverse solenoid 72. When coil 73 of solenoid 72 is energized, a clockwise motion is imparted to cam arm 70 as core 71 is attracted toward coil 73. Thus, clutch engaging cam 74 is caused to engage the lower side of winding spool clutch gear 59. This action causes clutch gear 50 to tilt to a position where several notches thereon engage notches of the winding spool gear 59 (Fig. 2). Thus, the rotational movement of main drive shaft 42 is imparted to winding spool 12 via the left winding spool clutch now engaged. It is to be observed in Fig. 6 that the tilting action referred to hereinabove is brought about when cam 74 engages clutch gear 50, due to the fact that the clutch gear openings 55 are of a slightly larger diameter than the drive pins 49.

When coil 73 (Fig. 6) is de-energized, return spring 75 imparts a counterclockwise motion to cam arm 70. As a result thereof, cam 74 is moved away from clutch gear 50, and spider spring 56 forces gear 50 away from winding spool gear 59 to thereupon disengage the left winding spool clutch.

As is shown in Fig. 5, in addition to being attached to clutch engaging cam arm 70, the solenoid core 71 is loosely connected by stud 79 to reinker arm 76 which, in turn, is fixed to vertical rod 77. Thus, the reinker roller engaging arm 78 which is also fixed to rod 77 is caused to move in a counterclockwise direction when reinker and reverse coil 73 is energized. The movement imparted thereto is sufficient to cause contact between reinker wick 35 and reinker roller 17. It is to be observed in Fig. 1 that the ribbon 10 is tensioned by the reinker rollers 17 and 21 notwithstanding the position of either of the said rollers with respect to its associated reinker wick. Due to this contact between the ribbon and the reinker rollers, both of the rollers are caused to revolve during the time that the ribbon is advancing in either direction. However, since only the reinker roller associated with the driven winding spool is in contact with its respective reinker wick, ink is applied to ribbon 10 only at a point, just prior to winding the ribbon onto a winding spool. With particular reference to the left hand ribbon feeding and reinking mechanism 40 shown in Figs. 1 and 5, one end of reinker wick 35 projects from reinker 80 so as to contact reinker roller 17 when coil 73 is energized. The other end of wick 35 is immersed in ink contained within the reinker cartridge 81. Reinker 80 is held in position on top of the printing machine by a reinker cartridge holder 82. In order to apply ink directly to the longitudinal ribbon area in use, reinker 80 is positioned within cartridge holder 82 so that wick 35 is in contact with an area on reinker roller 17 which is aligned with the upper longitudinal inking ribbon area, whereas reinker 89 is positioned within cartridge holder 90 so that wick 36 is in contact with an area on reinker roller 21 which is aligned with the lower longitudinal inking ribbon area.

Referring to Fig. 4, the ribbon shifting apparatus of the left hand ribbon feeding and reinking mechanism 40 includes in general a ribbon shifting arm 92 with ribbon roller guides 16 and 18 thereon, mounted on a pivot rod 84 and attached, at one end, to core 93 of the shift coil 86. When shift coil 86 is energized and core 93 is attracted thereto, a clockwise movement about pivot rod 84 is imparted to the shifting arm 92. This causes the ribbon roller guides 16 and 18 to move downwardly. This move-

ment is of a magnitude to present the upper longitudinal ribbon printing area to printing wheels 11 (Fig. 1). When shift coil 86 is de-energized, the return spring 87 causes the shifting arm 92 to move in a counterclockwise direction and ribbon roller guides 16 and 18 upwardly. This movement is of a magnitude to present the lower longitudinal ribbon printing area to printing wheels 11 (Fig. 1).

The ribbon shifting apparatus of the right hand ribbon feeding and reinking mechanism 41 is similar to the shifting apparatus just described. Thus, as shift coils 86 and 88 (Fig. 1) are energized and deenergized concurrently, the upper and lower longitudinal ribbon printing areas are presented to the line of printing wheels. As the description advances, the circuit for causing a shift in a transverse direction of the ribbon 10 at each ribbon reversal, will be explained.

Circuit description

As described hereinbefore, when eyelet 30 (Fig. 1) engages the switch actuating arm finger 31 so as to move switch actuating arm 14 counterclockwise, a lateral extension 32 of the said arm strikes the switch operating arm 33 of the left switch 34. Arm 14 is held in this position by trigger spring 91. As is shown in Fig. 3, the above-described action causes the switch contacts 95 to close the following circuit to energize relay coil R1-P: starting at terminal 97 of voltage source 98, to line 99, through contacts 95, through coil R1-P, to line 100, and to terminal 101 also of voltage source 98. When coil R1-P is energized its contacts R1-1, R1-2 and R1-3 are transferred so that the left reinker and reverse coil 73 is energized when contacts R1-1 close, the right reinker and reverse coil 101 is de-energized when contacts R1-2 open, and the left and right ribbon shift coils 86 and 88, respectively, are energized when contacts R1-3 close. Thus, the closing of switch contacts 95 of left switch 34 causes the left winding spool clutch to engage and the left winding spool 12 to be driven in a clockwise direction; the right winding spool clutch to disengage; the left reinker roller 17 to contact reinker wick 36; the right reinker roller 21 to be moved away from wick 36; and the shift mechanism to operate whereby the roller guides 16, 18, 20 and 22 are moved downwardly to present the upper longitudinal printing area of ribbon 10 to the line of printing wheels.

As the ribbon 10 starts to wind on winding spool 12 (Fig. 1), the eyelet 30 engages the switch actuating arm finger 108 so as to move arm 14 clockwise, and the lateral extension 32 away from operating arm 33. Arm 14 is held in this position by spring 91. This action opens contacts 95 and de-energizes relay coil R1-P. However, as the relay which is operated when coil R1-P is energized is a latch type relay, the contacts R1-1, R1-2 and R1-3 remain transferred. As is known in the art, a latch type relay is one which is mechanically maintained operative after the pick coil thereof is once energized. The contacts of this type of relay are returned to a normal position only after a latch trip coil is energized to disengage the mechanical latching means holding the contacts transferred.

When the eyelet (not shown) attached to the right end portion of ribbon 10 engages the switch actuating arm finger 103 (Fig. 1), the right switch contact 104 (Fig. 3) is caused to transfer; i. e., a lateral extension 105 (Fig. 1) of arm 23 strikes the switch operating arm 106 of the right switch 107. This action causes the following circuit to energize latch trip coil R1-T: starting at terminal 97, to line 99, through contacts 104 normally open, through coil R1-T, to line 100, and to terminal 101. The energization of coil R1-T disengages the mechanical latching means holding contacts R1-1, R1-2 and R1-3 transferred. Thus, the right reinker and reverse coil 102 is energized when contacts R1-2 close, and thereby causes the right winding spool clutch to engage and drive the right winding spool 13 in a counterclockwise direction.

The energization of coil 102 also causes the engagement of the right reinker roller 21 and the reinker wick 36. The left reinker and reverse coil 73 is de-energized when contacts R1-1 open, as are the shift coils 86 and 88 when contacts 104 transfer. This causes the left winding spool clutch to disengage, and the lower longitudinal printing area of ribbon 10 to be presented to the line of printing wheels.

Summary

In summation, when the eyelet 30 (Fig. 1) attached to the left end portion of continuously advancing ribbon 10 engages finger 31, the electrical contact within left switch 34 is rendered closed. This completes an electric circuit whereby left reverse and reinker coil 73 and left and right shift coils 86 and 88, respectively, are caused to be energized, and opens an electric circuit whereby right reverse and reinker coil 102 is caused to be de-energized. As a result of the foregoing, the direction of feed of ribbon 10 is reversed so that the ribbon is wound on winding spool 12, and the point of ribbon reinking is changed from reinker roller 21 to roller 17. In addition thereto, ribbon 10 is shifted in a transverse direction so as to present the upper longitudinal printing area of the ribbon to printing wheels 11.

When the eyelet attached to the right end portion of ribbon 10 engages finger 103, the electric contact within right switch 107 is transferred. This completes an electric circuit whereby right reverse and reinker coil 102 is caused to be energized, and opens an electric circuit whereby left reverse and reinker coil 73 and left and right shift coils 86 and 88, respectively, are caused to be de-energized. Thus, the direction of feed of ribbon 10 is once again reversed, and the ribbon is now wound on winding spool 13 while being reinked by reinker roller 21. In addition thereto, the de-energization of shift coils 86 and 88 causes ribbon 10 to be shifted in a transverse direction so that the lower longitudinal printing area of the ribbon is presented to the printing wheels 11.

While there have been shown and described and pointed out the fundamental novel features of the invention as applied to a preferred embodiment, it will be understood that various omissions and substitutions and changes in the form and details of the device illustrated and in its operation may be made by those skilled in the art, without departing from the spirit of the invention. It is the intention, therefore, to be limited only as indicated by the scope of the following claims.

What is claimed is:

1. A mechanism for operating upon an inking ribbon on a machine having printing members in a printing station comprising a pair of drivable winding spools on which the inking ribbon is adapted to be wound on opposite sides of the printing station, a pair of ribbon reinking devices arranged on opposite sides of the printing station, electric control means to render alternately operative each one of said pair of reinking devices for spreading ink on the inking ribbon, means governed by said control means to shift the inking ribbon whereby a succeeding one of a plurality of superposed ribbon printing areas is positioned in printing alignment with the printing members, means governed by said control means to alternately drive each one of said winding spools so that the inking ribbon is moved alternately in forward and reverse directions, and electric circuit means including a first switch under the control of the inking ribbon moving in a forward direction and a second switch under the control of the inking ribbon moving in a reverse direction to control said control means for governing said winding spool driving means, said reinking device operating means, and said ribbon shifting means so as to automatically and concurrently change the direction of ribbon movement, shift the inking ribbon to a succeeding ribbon printing area, and alter the point of ribbon reinking.
2. In a mechanism for operating upon an inking ribbon on a machine having printing members thereon, wherein

the inking ribbon has attached thereto a switch operating element at approximately each end thereof; a pair of drivable winding spools on which the inking ribbon is adapted to be wound; a winding spool drive mechanism; a pair of engageable clutches each of which is associated with one of said pair of winding spools to connect said winding spools to said drive mechanism; a pair of reinking devices for reinking the inking ribbon; means for mounting each of said reinking devices for movement relative to the inking ribbon; means to shift the inking ribbon in a transverse direction so that superposed ribbon printing areas running lengthwise of the inking ribbon are alternately placed in printing alignment with the printing members; a first electric switch associated with one of said winding spools; a second electric switch associated with the other of said winding spools; a first solenoid for engaging one of said clutches and moving one of said reinking device mounting means; a second solenoid for engaging the other of said clutches and moving the other of said reinking device mounting means; a third solenoid for controlling said ribbon shift means; and electric circuit means including said solenoids under the control of said switches, to simultaneously energize said first solenoid and said third solenoid and de-energize said second solenoid when a switch operating element attached to one end of the inking ribbon renders said first switch operative, and to simultaneously energize said second solenoid and de-energize said first solenoid and said third solenoid when a switch operating element attached to the other end of the inking ribbon renders said second switch operative, thereby moving the inking ribbon in forward and reverse directions alternately for substantially its full length, shifting the inking ribbon so that superposed ribbon printing areas are placed in printing alignment with the printing members alternately, and changing the point of ribbon reinking.

3. A mechanism for operating upon an inking ribbon on a machine having printing members in a printing

station comprising a pair of drivable winding spools on which the inking ribbon is adapted to be wound on opposite sides of the printing station; a pair of ribbon reinking devices arranged on opposite sides of the printing station; control means including a first, a second and a third electrical device, means governed by said first and said second electrical devices to render alternately operative each of said pair of reinking devices for spreading ink on the inking ribbon, means controlled by said third electrical device to shift the inking ribbon whereby a succeeding one of a plurality of superposed ribbon printing areas is positioned in printing alignment with the printing members, means controlled by said first and said second electrical devices to alternately drive each of said winding spools so that the inking ribbon is moved alternately in forward and reverse directions, and electric circuit means including a first switch under the control of the inking ribbon moving in a forward direction and a second switch under the control of the inking ribbon moving in a reverse direction to govern said control means; said first switch being effective to cause said first and said third electrical devices to operate and said second switch being effective to cause said second electrical device to operate so as to automatically and concurrently change the direction of inking ribbon movement, shift the inking ribbon to a succeeding ribbon printing area, and alter the point of ribbon reinking.
